Joseph J. Watson ATTORNEY

UNITED STATES PATENT OFFICE.

ALBERT ATWOOD, OF SEATTLE, WASHINGTON.

DESIGN FOR A SPOON.

No. 39,555.

Specification for Design.

Patented Sept. 22, 1908.

Application filed July 21, 1908. Serial No. 444,679. Term of patent 7 years.

To all whom it may concern:

Be it known that I, ALBERT ATWOOD, a citizen of the United States, residing at Seattle, county of King, State of Washington, have invented a new, original, and ornamental Design for Spoons, of which the following is a specification, reference being had to the accompanying drawing, forming part thereof.

Figure 1 is the obverse view of the spoon, showing the design, and Fig. 2 is the reverse view thereof.

I claim:

The ornamental design for a spoon, as shown.

ALBERT ATWOOD.

Witnesses:

JOS. MAYER,
W. S. McKEAN.
